UNITED STATES PATENT OFFICE.

ELIJAH T. GASKILL, OF NEW BERNE, NORTH CAROLINA, ASSIGNOR OF ONE-HALF TO CAROLINE D. PATTERSON, OF SAME PLACE.

MATTRESS-FILLING MACHINE.

SPECIFICATION forming part of Letters Patent No. 530,040, dated November 27, 1894.

Application filed June 26, 1894. Serial No. 515,785. (No model.)

To all whom it may concern:

Be it known that I, ELIJAH T. GASKILL, residing at New Berne, in the county of Craven and State of North Carolina, have invented 5 a new and Improved Mattress-Filling Machine, of which the following is a specification.

My invention has for its object to provide a mattress filling machine, of a simple construction, easily manipulated, and which will quickly and effectively serve for its intended purposes.

The invention consists in such novel features of construction and peculiar combination of parts as will be hereinafter first described in detail and then be particularly pointed out in the appended claims, reference being had to the accompanying drawings, in which—

20 Figure 1 is a perspective view of the machine the traveling chamber or box being in position to receive the filling material. Fig. 2 is a plan view of the same showing the filling compressing arms in place and the box 25 ready to be moved into the ticking. Fig. 3 is a similar view showing the box and filler within the ticking and the presser in position, the box being shown moved back outside the ticking, in dotted lines. Fig. 4 is an 30 end view taken from the center post end. Fig. 5 is a cross section taken on the line 5—5 Fig. 2. Fig. 6 is a detail perspective view of the presser bar, and Fig. 7 is a similar view 35 of the removable tail piece. Fig. 8 is a detail perspective view of one end of the box showing the pivotal connection of the lever.

In its practical construction my improved machine comprises a main frame A, formed of the supporting legs a a the horizontal 40 brace beams a' a' and the bed portion a², which for more than half its length has at the side edges, strips a³ which form guides for the carriage or movable box B. The box B has an open front end, side members b b and 45 a rear end portion b', provided with an opening b² for a purpose presently explained.

C indicates a transverse strip secured to the back of the box, which has a central extension c and projecting ends c' c' having eye 50 bolts c² c², to which are connected chains or ropes D, which extend forward and pass over

pulleys e e in vertically adjustable standards E secured to the main frame, and then rearward, their free ends being wound about and secured to a winding shaft F journaled transversely on such frame as shown most clearly in Fig. 5.

G indicates a chain or rope secured at one end to the extension c on the rear of the box B, which passes over a pulley h, journaled in 60 a vertically adjustable standard H extended up through the bed of the main frame centrally, at the rear end, and then forwardly under the bed, its free end being secured to and wound about the shaft F, in an opposite 65 direction to the winding of the cords D.

So far as described it will be readily understood that by turning the shaft F (by means of the crank handle f), in opposite directions the box B can be slid forward or rearward on 70 the table as may be desired, and as the chain rollers e and h are held in vertically adjustable bearings they can be quickly set so as to keep the chains in a proper position for a straight pull.

75 J J are standards which project up one at each side of the frame, at a point in line with the front end of the box B, when it is at its rearmost position and to such standards at the upper end, is attached a transverse rod K 80 the ends of which are extended to form arms k' k' on which are held spring clamps L L.

M indicates a metal sheet held on the table, its rear end being secured thereto while its front end, which extends to a point in line 85 with the side posts E E is loose to allow for a free movement thereof for a purpose herein-after described.

N indicates a detachable tail piece provided with prongs or spurs n at its lower edge, which 90 piece is used to close the front end of the box B when the filling material is placed therein, the spurs holding the lower edge in place, while the upper end is held by a cord O, one end of which is connected to the rear end of 95 the box at one side, while the free end passes over the front end under guides o o and then rearward where it connects with an eye o² after the cord has been tightly drawn.

P P indicate a series of compressing levers 100 which have pendent loop members p p at their handle portions p' p', which are adapted to

engage with either one of a series of transverse bearing rods Q secured on the back end of the box B, such members p forming, as it were, fulerums for the levers. These levers 5 pass through notches or seats $b \times b^x$ in the top of the rear wall of the box, extend longitudinally the length of such box and have at their ends notches on the upper face as at P^x P^x to engage the cord O as shown in Fig. 2.

10 R indicates a follower or compressing block which before the box is filled is placed at the rear end of the box and covers the opening therein.

15 S indicates a compressing bar, which has a head portion s formed with spurs s' which head is of a size to freely enter the opening in the rear end of the box, while the rear end has a tenon S^x which is adapted to fit an aperture H^x in the post H.

20 The operation of my improved machine is best explained as follows: The box B is first drawn back to the position shown in Fig. 1, the follower or presser block R, fitted in the rear end, the tail board at the front end, and 25 the cord O secured in position. The desired quantity of filling material is then thrown in the box, and the tail board N removed. The filling is then compressed by the levers which are forced down until their front notched 30 ends engage the cord O. The lower side of the ticking is then slipped under the plate M up to the front end of the box B, and the upper front end thereof lapped over the rod K and clamped thereto by the clamps L. The box 35 with the compressed filling is then moved through the medium of the shaft D and operating cords outward into the ticking as indicated in Fig. 2. The bracing cord O is then loosened at the ends and drawn out from 40 around the box. The clamps are also preferably removed. The pressing bar is then inserted with its head s bearing against the board R, and its end s' fitted in the hole h^x of the post H. The box is then withdrawn 45 from the tick by the reversing motion of the shaft F, leaving the stuffing inside of the tick. The wire clamps L are now unfastened and the tick removed, and ready for sewing.

Having thus described my invention, what 50 I claim, and desire to secure by Letters Patent, is—

1. A mattress filling machine, comprising a table frame, having tick holding devices, a 55 filler holding carriage or box held to reciprocate on the table, having filler compressing devices and means for reciprocating the carriage into and out of the ticking substantially as shown and described.

2. In a mattress filling machine the combination with the supporting frame or table, the reciprocating carriage and means for holding the upper front end of the tick, of a plate held on the bed having its front end movable upward and adapted to fit over the bottom of 65 the tick and means for reciprocating the carriage substantially as shown and described.

3. A mattress filling machine comprising a

main frame, having a table or bed portion, a box or filling holding carriage held to be reciprocated longitudinally, having an open front end, means for reciprocating the said carriage a strain cord passed over the front, and a removable tail piece adapted to close such front, held from outward movement by such strain cord all substantially as shown 70 and for the purposes described.

4. In a mattress filling machine the combination with the main frame, having tick holding and securing portions and a fixed post at one end, of a reciprocating carriage or filler 80 holding box, having an open front end and having its rear end formed with an opening, means for reciprocating such carriage and a detachable presser bar having one end adapted to fit through such opening and the 85 other to fit against the fixed post, when the said box is moved forward into the ticking all substantially as shown and described.

5. In a mattress filling machine in combination with the tick holding and supporting 90 devices of a reciprocating carriage having an open front end, its rear end having an opening, and a follower or presser board of a detachable presser bar adapted to be fitted with its front end projected through the rear 95 end of the box against the filler and fixedly held, and means for reciprocating the box all substantially as shown and described.

6. In a mattress filling machine the combination with the main frame and tick holding 100 devices, of a reciprocating filler holding carriage or box, having an open front end a detachable cord held over such front end, presser levers fulcrumed at the rear end of the box adapted to swing down against the 105 filler, and to extend under and engage the said cord, and means for reciprocating the carriage all substantially as shown and described.

7. In a mattress filling machine substantially as described, a reciprocating filler carriage having an open front end, a strain cord detachably connected therewith passed over such end, presser levers having fulcrum members adjustably connected with the rear end 115 of the box, and having notched front ends adapted to engage the strain cord and means for reciprocating the carriage all arranged substantially as shown and described.

8. The combination with the main frame, 120 the reciprocating carriage, and the metal sheet M loosely held on the frame, of the rod K held transversely over the front end of the carriage when at its rearmost position said rod having clamp members L and means for 125 reciprocating the carriage all arranged substantially as shown and described.

9. The combination with the main frame, 130 the apertured post H the reciprocating carriage having an open front end, its rear wall having an aperture, and the detachable presser board R, of the presser bar S having a head portion adapted to extend through the rear wall of the carriage, and bear against

the board R, and having tenon portion adapted to seat in the apertured post H, and means for reciprocating the carriage all arranged substantially as shown and described.

5 10. The combination with the main frame, the shaft F the standards E E and post H having pulleys e and h respectively of the carriage B having an open front end, and provided with clamp levers, and having a 10 transverse strip C formed with a central ex-

tension c and end projections c' c' the cords D secured to the end projections c passed over pulleys e and secured to shaft F and the cord G secured to the extension c passed over pulley h and secured to the shaft F all arranged substantially as shown and described. 15
